(57) **CLAIM**

I claim the ornamental design for a wine bottle stand, as shown and described.

DESCRIPTION

FIG. 1 is a perspective view of a wine bottle stand, showing my new design.

FIG. 2 is a front view of the wine bottle stand of FIG. 1.

FIG. 3 is a rear view of the wine bottle stand of FIG. 1.

FIG. 4 is top view of the wine bottle stand of FIG. 1.

FIG. 5 is a bottom view of the wine bottle stand of FIG. 1.

FIG. 6 is a left-side view of the wine bottle stand of FIG. 1.

FIG. 7 is a top plan view of the wine bottle stand shown in a flattened configuration; and,

FIG. 8 is a perspective view of the wine bottle stand shown in a configuration of use.

The dashed broken lines in FIG. 8, showing a bottle, represent environment and form no part of the claimed design.

1 Claim, 8 Drawing Sheets
